ART OF ATTACHING HEELS TO SHOES

Francis Low Brandt, Wakefield, Mass., assignor
to United Shoe Machinery Corporation, Paterson, N. J., a corporation of New Jersey

Application August 28, 1936, Serial No. 98,371

5 Claims. (Cl. 12—147)

My invention relates to the attachment of heels to shoes, it particularly involving the securing of the heels by fastenings driven from within the shoes.

5 In the heelings of women's shoes, especially those as of the Louis type having sharply curved side-walls, it is difficult to obtain the desired firm connection and a close rand-crease without causing the fastenings to split the heel or to emerge 10 through the side-walls. It is an object of this invention to bring about the result sought by a simple manner of heel-attachment, readily accomplished.

A feature of the invention lies in a method 15 of attaching heels to shoes in which a fastening, made tubular by the presence of a longitudinal passage within it, is forced through the heel-seat of a shoe into a heel positioned on the heel-seat and is caused to penetrate said heel-seat and 20 heel and retain within it a portion of the heel-material. Since this inner portion is separated from the outer by the wall of the tube, it is not displaced outwardly as the fastening is driven 25 into the heel, and consequently the splitting effect upon the heel is greatly reduced. This being true, the diameter of the fastening may be relatively great without danger of causing damage to the heel, and because of this large diameter, the security of retention is increased, and 30 the retaining effect is carried outwardly toward the crease, tending to make this closer. The attachment is more effective than that furnished by a plurality of such fastenings as nails. If, however, it is desired to further increase the integrity of the connection, a group of nails may 35 be driven through the heel-seat into the heel outside the tubular fastening, this operation preferably being performed at a different time from that at which the inner fastening is driven. The 40 strain upon the work and upon the driving means is thus reduced.

Another feature of the invention may be found in a shoe having a heel attached in the manner I have just outlined. Here, a tubular 45 fastening extending through the heel-seat portion of the shoe-sole and into a heel thereon has within its tubular portion a portion of the heel-material which it divides from the remainder of the heel. This enclosed portion exerts no lateral 50 rupturing thrust upon the body of the heel and by its connection to said body and its frictional engagement with the inner wall of the tube-passage, offers some resistance to displacement of the heel. The exterior of the fastening preferably has projections to increase the retentive ef-

fect. With the tubular fastening, a group of nails driven between it and the side-wall of the heel may or may not be employed.

My improved manner of heel-attachment and a machine by which the method of effecting the attachment may be performed are illustrated in the accompanying drawing, in which

Fig. 1 is a partial, vertical section taken transversely of the machine;

Fig. 2 is a similar enlarged section through the upper portion of the jack, more particularly showing the shoe-construction, and

Fig. 3 is a perspective view of the fastening employed for the attachment, further enlarged and with a portion broken away.

Referring particularly to Fig. 2 of the drawing, there is shown a shoe S, upon the heel-seat portion of a sole s of which is positioned a heel H. Near the longitudinal or heightwise axis of the heel passes a fastening F, which appears in Fig. 3 separated from the heel. The fastening is tubular, having a relatively thin, cylindrical body b through which is a longitudinal passage l. A reduced penetrating edge e about one extremity of the passage is adapted to cut its way through the heel-seat and heel-material when pressure is applied to a head h in the form of a flange encircling the opposite end of the passage. From the body b, preferably beginning near the edge e and extending for a considerable distance toward the head, is a projection, which may be in the form of a continuous helix p. Considering a transverse section of any convolution of this helix, there is a surface x lying approximately at right-angles to the axis of the fastening, and 20 diverging from this surface is a surface y which is inclined inwardly toward the fastening-end at e. The inclination of the surface y, by forcing aside the material penetrated, facilitates the insertion of the fastening, while the angle of the 25 surface x, substantially 90° to the direction of movement, offers a maximum resistance to withdrawal. As the fastening F enters the work, the edge e cuts out a cylinder m of the material constituting the heel-seat of the shoe and of the 30 heel. This is received in the passage l, resistance to its entrance being reduced by an opening through the head h, this opening permitting the escape of air which would otherwise be compressed by the entrance of the cylindrical portion 35 m into the fastening-passage. Were the fastening F solid, the material m would necessarily be thrust laterally upon the entrance of the fastening and would add so much to the expansive or bursting effect upon the heel H. Received with-

55

in the fastening, however, the heel is entirely shielded from its influence by the surrounding wall of the fastening-body *b*. When the insertion of the fastening has been completed, with the 5 head *h* sunk in the heel-seat material, the cylinder *m* will remain joined to the body of the heel in the plane of the cutting edge *e*. Therefore, the friction between the portion *m* and the wall of the passage *l* is added to the retaining 10 effect of the exterior of the fastening-body *b* and its engaging projection or projections *p*. This frictional retentive effect exerted within the fastening may be increased by slightly inclining inwardly the inner wall of the cutting edge *e*. 15 By doing this, a greater area will be included in the heel-portion *m*, and this will be compressed as the fastening forces it into the remainder of the passage, which is of smaller diameter. Because a fastening *F* of considerable diameter 20 may be driven without danger of splitting the heel, its periphery will lie closer to the edge of the heel-cup than could that of a solid fastening, and its effect in drawing this edge toward the heel-seat is increased, resulting in a tight 25 crease. If it is desired to add to the drawing and holding action of the fastening, a group of nails *N* of any suitable form and number may be driven, these surrounding the fastening *F*, occupying substantially their customary positions for a 30 nailed heel.

In performing the method of this invention to produce my improved shoe, the fastening *F* and the nails *N*, if the latter are employed, may be driven by hand, or a machine may be utilized. 35 An apparatus adapted for this purpose is disclosed in the application in my name for Letters Patent filed in the United States Patent Office on August 28, 1936, Serial No. 98,372. Of this machine, which is a modification of that disclosed in Letters 40 Patent of the United States No. 2,033,158, Standish, March 10, 1936, there appears a portion of a frame *10* having journaled in it a horizontal driving shaft *12* by which a driver-plunger *P* is reciprocated vertically in the frame. At the top 45 of the frame a shoe-supporting jack *14* is mounted, and co-operating with this jack is the usual heel-pressure-abutment *16* carried by side-rods *18, 18* guided in the frame at opposite sides of the jack. Fluid means (not illustrated) joins the 50 plunger to the heel-abutment in such a manner that the pressure applied by the latter varies with the resistance encountered by the plunger during the driving stroke.

To permit the fastening *F* and the nails *N* to 55 be inserted during succeeding portions of an operating cycle, the plunger *P* is formed in two parts, an outer portion *20*, which is guided for vertical reciprocation in the frame and which is tubular, and an inner portion *22* reciprocating 60 within the outer portion. Upon a sleeve *24* threaded into the upper extremity of the plunger *20* is separably carried a driver-plate *26*, and into this plate is threaded for individual, vertical adjustment a set of outer drivers *28*, each having a 65 lock-nut *30*. This set may be five in number. The inner plunger *22* is threaded at its upper end to receive an inner driver *32*, of greater diameter than the drivers *28* to properly support and insert the relatively large fastening *F*. Upon the driving shaft *12* is a cam consisting of spaced sections *60, 60*. The shaft is also sectional, the cam-sections being carried by the adjacent, spaced 70 ends of the shaft. Joining the inner faces of the cam-sections is an eccentrically placed crank-pin

62. The outer and inner plungers have lower terminal-portions *64* and *66*, respectively. The former portion is guided in the frame and is provided with spaced ends to which may be attached wear-plates *68, 68* resting upon the cam-sections 5 *60, 60*. The plunger *20* with its drivers *28* are held down, with the wear-plates urged toward the cam, by an expansion-spring *70* surrounding the body of the plunger and interposed between the terminal-portion *64* and the frame *10*. The terminal-portion *66* of the inner plunger *22* is guided within its companion portion *64* and is joined by a connecting rod or link *72* to the crank-pin *62*. The relation of the crank-pin to the portion of the cam of maximum diameter may be such that it causes the extreme upward movements of the drivers *28* and *32*, respectively, substantially 180° apart during the rotation of the driving shaft *12*. Therefore, while the drivers *28* are inserting a load of nails the driver *32* is resting, and conversely. By thus successively inserting the fastening *F* and a group of nails *N*, the clamping force which must be applied by the heel-abutment *16* may be considerably reduced without danger that the upward thrust of the fastenings shall displace the heel. Were this to occur, the nails might not be driven properly, and there might result a gaping crease. Further, the strain upon the machine elements is reduced by this division of the driver-action. 25

Having described my invention, what I claim as new and desire to secure by Letters Patent of the United States is:

1. The method of attaching heels to shoes, which consists in forcing through the heel-seat of a shoe into a heel positioned thereon a fastening within which is a longitudinal passage, thereby causing said fastening to penetrate the heel-seat and heel and retain within its passage a portion of the heel-material. 35

2. The method of attaching heels to shoes, which consists in driving through the heel-seat of a shoe into a heel positioned thereon a tubular fastening, causing said fastening to penetrate the heel-seat and the heel near the longitudinal axis of the latter, said fastening retaining within it a portion of the heel-material, and driving a group of nails through the heel-seat of the shoe into the heel outside the tubular fastening. 45

3. The method of attaching heels to shoes, which consists in driving through the heel-seat of a shoe into a heel positioned thereon a tubular fastening, causing said fastening to penetrate the heel-seat and the heel near the longitudinal axis of the latter, said fastening retaining within it a portion of the heel-material, and driving a group of nails through the heel-seat of the shoe into the heel outside the tubular fastening, the tubular fastening and nails being driven at different times. 55

4. A shoe comprising a sole and a heel attached to the heel-seat-portion of the sole by a tubular fastening extending through the sole into the heel and having within its tubular portion a portion of the heel-material. 60

5. A shoe comprising a sole and a heel attached to the heel-seat-portion of the sole by a tubular fastening extending through the sole into the heel and having a projection upon its exterior engaging said heel, there being within the tubular portion of the fastening a portion of the heel-material. 65

FRANCIS LOW BRANDT.
